(57) **CLAIM**

The ornamental design for a flexible pipe, as shown and described.

DESCRIPTION

The patent or application file contains at least one drawing executed in color. Copies of this patent or patent application publication with color drawing(s) will be provided by the Office upon request and payment of the necessary fee.

FIG. 1.2 is a perspective view of a flexible pipe, showing my new design in a fuchsia color;

FIG. 1.3 is an end view of the flexible pipe shown in FIG. 1.2;

FIG. 3.2 is a perspective view of a flexible pipe, showing my new design in a turquoise color; and

FIG. 3.3 is an end view of the flexible pipe shown in FIG. 3.2

The break lines indicate that no particular length is claimed, and any portion shown between the breaks forms no part of the claimed design.
